UNITED STATES PATENT OFFICE.

JACOB LAMBERTY, OF KEWANEE, ILLINOIS, ASSIGNOR OF ONE-HALF TO BENJ. WAHL, OF KEWANEE, ILLINOIS.

PIPE-PULLER.

No. 915,866.

Specification of Letters Patent. Patented March 23, 1909.

Application filed December 14, 1906. Serial No. 347,848.

To all whom it may concern:

Be it known that I, JACOB LAMBERTY, a citizen of the United States, residing at Kewanee, in the county of Henry and State of Illinois, have invented a new and useful Improvement in Pipe-Pullers, of which the following is a specification.

This invention relates to pipe pullers and more particularly to devices for handling pipes from furnaces, the object being to provide a device that will grip a pair of tongs carrying the pipe and draw the same outwardly as the pipe comes out of the furnace.

With this and other objects in view, the invention consists in the novel features of construction, combination and arrangement of parts hereinafter fully described and pointed out in the claims.

In the drawings forming a part of this specification:—Figure 1 is a perspective view of my improved pipe puller. Fig. 2 is a top plan view of a portion of the same. Fig. 3 is a detail sectional view showing the manner of connecting the bench to the stand. Fig. 4 is a side elevational view of the puller showing the jaw of the carrier open. Fig. 5 is a side elevational view of the puller, showing the jaw of the carrier closed on a pipe of tongs. Fig. 6 is a section taken on lines 6—6 of Fig. 4. Fig. 7 is a perspective view of the carrier. Fig. 8 is a perspective view of the jaw. Fig. 9 is an inverted perspective view of the carrier.

Referring to the drawings A and B indicate a pair of slotted legs on which is mounted a top C which is connected to the legs A by braces forming a stand. One end of the top C projects out beyond the leg B and is reduced at C'. A strip E is secured under the reduced end C' of the top C, between which is pivotally mounted on a pin F, the reduced end G', of the top of a bench G, which is supported by legs G², G³ connected thereto by braces G⁴, G⁵. The top of the bench is provided with a longitudinal slot to each side of which is secured a track H on which is mounted the carrier block I, which is provided with downwardly projecting sides I', adapted to fit over said track. The carrier block is provided with a beveled front end I² and the top is cut out at I³ and inclined downwardly at I⁴, and bifurcated at I⁵ having apertured enlargements forming bearings I⁶ in

which is mounted a pin J on which is mounted the apertured shank K', of a curved jaw K, which is adapted to clamp the tongs on the same when being pulled outwardly. The shank of the jaw projects downwardly through the slot in the bench and is provided with a slot K², adjacent its end in which is mounted a rod L, provided with an eye at each end to one end of which one end of a cable M, is connected, which is twisted once or twice around a grooved pulley N, carried by a shaft O, mounted in brackets O', secured to each side of the slot of the leg A. The cable is then extended forwardly up over a pulley P, mounted in bearings P', secured to each side of the slot in the leg G², of the bench and is connected to the eye at the other end of the rod L, so that the carrier can be worked back and forth on the track and it will be seen that the jaw will be drawn downwardly on the carrier when traveling outwardly so as to grip the pipe and will be drawn open as it travels backwardly so as to release the pipe. A drive wheel Q is fixed on the end of the shaft O, to which is adapted to be connected an electric motor for operating the same.

At the present time, wrought iron pipes are pulled by a chain which is very clumsy and expensive, as it requires three men to hook the tongs carrying the sheet of metal to the chains, while with my improved puller, one man can do the same work as all the man has to do is to clamp a pair of tongs on a sheet of metal in the furnace when it reaches the right heat, then place on a bell which is adapted to be arranged in a head-block 90 adapted to be secured on the end of the bench all of which are of the ordinary construction. As the carrier block on the bench comes to the end of the bench and is reversed the jaw of the same will close on the tongs 95 automatically and draw the sheet of metal through the bell forming it into a pipe and as the carrier reaches the other end of the bench and is reversed, the jaw will be opened automatically so that the tongs can be readily taken out.

Having thus fully described my invention, what I claim as new and desire to secure by Letters Patent is:—

1. The combination with a bench having a slot formed therein, of a carrier mounted on

said bench provided with a jaw having a shank working in said slot and connected to a cable for the purpose described.

2. In a device of the kind described, the 5 combination with a bench having a longitudinal slot formed therein; of a track secured on said bench, a carrier arranged on said track, a pivoted jaw carried by said carrier working in said slot, and a cable connected to 10 said jaw, for the purpose described.

3. In a device of the kind described, the 15 combination with a bench having a slot formed in its top, of tracks secured to the top of the bench to each side of said slot, a carrier mounted on said tracks, a jaw pivotally mounted on said carrier having a slotted shank extending down through said slot in

the top of the bench and a rod working in said slot and a cable connected to said rod, for the purpose described.

4. In a device of the kind described, the 20 combination with a bench, having a slot formed in its top, of a carrier mounted on said top, a jaw pivotally mounted on said carrier provided with a slotted shank extending down through said slot in the top of the bench, a rod working in said slot and a cable connected to the ends of the rod, for the purpose described.

JACOB LAMBERTY.
